Patented Feb. 27, 1923.

UNITED STATES PATENT OFFICE.

EUGENE WILLIOME, OF ST. LOUIS, MISSOURI.

SQUARE.

Application filed December 12, 1921. Serial No. 521,646.

To all whom it may concern:

Be it known that I, EUGENE WILLIOME, a citizen of the United States, residing at St. Louis, Missouri, have invented a new and 5 useful Improvement in Squares, of which the following is a specification.

This invention relates to an improvement in squares, and consists in the novel construction hereinafter described.

10 An object of the invention is to provide a square having one arm in the form of a straight edge rule and the other arm connected therewith, the second arm comprising pivoted sections arranged to move on a vertical axis to either side preserving the continuity of the side faces of the arm.

Additional advantages of the construction will be apparent from the following detailed description thereof, taken in connection with 20 the accompanying drawing in which

Fig. 1 is an elevation of the complete square.

Fig. 2 is a plan view.

Fig. 3 is a vertical section taken substantially on the line 3—3 of Fig. 4.

Fig. 4 is a cross section taken on the line 4—4 of Fig. 1.

Fig. 5 is a cross section taken on the line 5—5 of Fig. 1.

30 Fig. 6 is a diagrammatic view showing application of the square in connection with an irregularly shaped piece of work.

The square of the present invention is particularly adapted for accurate work, such 35 as work on irregularly shaped patterns for castings or the like, and has many special features and advantages adapting it for such work as an instrument of precision.

In the embodiment of the invention illustrated in the drawing the arm 1 thereof is 40 in the form of a straight edge rule having graduations on one face and having a slot 2 in the rear face thereof. The other arm is made up of a plurality of sections, the 45 section joined to the rule being in the form of a block 3 having a slot 4 therein that constitutes a seat for the edge of the rule 1 and into which said rule 1 is fitted.

The block 3 has a cut-out portion 5. In 50 order to clamp the block 3 in connection with the rule 1 a releasable clamp device comprising a lock member including a body 6 having an inwardly extending flange or bead 7 is mounted in an opening 8 through 55 the wall of the block 3 intermediate of the cut-out portion 5 or slot 4, the bead 7 engag-

ing in the slot 2 in the back face of the rule. Said lock member is provided with an actuator including a stem 9 upon which is mounted a member 10 having a cam face 11. 60 The member 10 is revoluble on the stem 9 and is held from displacement therefrom by a washer 12. The washer 12 is of the familiar split type in which a slot runs from the hole to one side of the washer, permitting 65 the washer to be applied to and removed from the stem 9 while the member 10 is on the stem. The washer engages a reduced portion of the stem 9, the inner end of which seats in a recess in an extension 17 of the 70 block 3 (Figs. 3 and 4). A spring 13 is nested in a cavity in the outer face of the member 10 and bears against the washer 12. The cam face of the member 10 cams against an inclined wall 14 of the cut-out 75 portion 5. Thus as the member 10 is rotated the lock member is moved inwardly and outwardly to release and to clamp the block 3 in connection with the rule 1 so that the block 3 may be adjusted to any desired 80 longitudinal position on the rule and, after the adjustment is effected, may be clamped from displacement. It will, of course, be understood that the specific form of clamp device described may be modified and other 85 forms may be employed if desired.

As illustrated in the drawing the second section of the adjustable arm is in the form of a link including a body portion 15 having horizontally extending flanges 16, the 90 flanges 16 being rounded at the ends. A rounded extension 17 at the end of the block 3 is so formed as to be received between the flanges 16 and has an opening therein to register with openings in the flanges 16 to receive a tapered pivot pin 18. A cavity 19 is formed in the body of the link 15 in which is mounted a plate 20, said plate being actuated outwardly by a spring 21 in the cavity back of the plate. The front edge of the 100 plate is beveled as indicated at 22, the edge 22 abutting against the rounded surface of the extension 17. The extension 17 has a vertical slot formed therein, so that when the link and block are in longitudinal alignment they will be locked in adjustment. As the plate 20 is actuated against the rounded surface of the extension 17 a sufficient frictional engagement is maintained so as to hold the block and link in relative adjustment when the link is moved from the longitudinal adjustment. 110

The arm of the square may include any desired number of links constructed as described, it being understood that the terminal link instead of having a projection has a 5 plane vertical face as indicated at 23.

A square constructed in accordance with the invention has numerous applications and may be employed on a great variety of work. In Fig. 6 one application is illustrated in 10 which the square is shown applied to a cylindrical structure 24 having a reduced cylindrical extension 25. The flexible arm of the square may be curved about the reduced cylindrical portion 25 holding the rule section in a perfect vertical plane.

All of the edges of the flexible section of the rule are arranged in the same plane so that the square may be used for ruling straight lines, regardless of the contour of 20 the object to which it is applied. The square is also useful by reason of the flexible extensions for squaring up on work having parallel surfaces where the surfaces are in such close proximity that it would be impossible to insert the lateral arm of the 25 square, if the arm was fully extended. Many other uses will be found for the device, particularly on work that requires great accuracy.

I am aware that the invention may be modified in various particulars without departing from the spirit and scope thereof. I do not limit myself to unessential details of construction and arrangement.

What I claim and desire to secure by Letters Patent, is:—

1. A square, comprising a flat, elongated member, and a lateral member slidably mounted on the elongated member, said 40 lateral member being composed of pivoted

sections whereby the sections may be moved to either side of the plane of the elongated member.

2. A square, comprising a flat, elongated member, and a lateral member slidably 45 mounted on the elongated member and comprising a plurality of sections pivoted together on axes parallel to each other, said axes being also parallel to the longitudinal axis of the elongated member.

3. A square, comprising a flat, elongated member, and a lateral member slidably mounted on the elongated member and comprising a plurality of sections pivoted together on axes parallel to each other, said 50 axes being also parallel to the longitudinal axis of the elongated member, and frictional devices for holding the sections in longitudinal alinement.

4. A square, comprising a flat, elongated member, and a lateral member slidably 60 mounted on the elongated member and comprising a plurality of sections pivoted together on axes parallel to each other, said axes being also parallel to longitudinal axis 65 of the elongated member, and clamping means for holding the two sections of the square in locked engagement.

5. A square, comprising a flat, elongated member, and a lateral member slidably 70 mounted on the elongated member and comprising a plurality of sections pivoted together on axes parallel to each other, said axes being also parallel to the longitudinal axis of the elongated member, clamping 75 means for holding the two sections of the square in locked engagement, and frictional devices for holding the sections in longitudinal alinement.

EUGENE WILLIOME.
